(57) **CLAIM**

The ornamental design for a camera as shown and described.

DESCRIPTION

FIG. 1 is a front view of a camera showing a new design;
FIG. 2 is a rear view thereof;
FIG. 3 is a right side view thereof;
FIG. 4 is a left side view thereof;
FIG. 5 is a top view thereof;
FIG. 6 is a bottom view thereof;
FIG. 7 is a top, front, and left perspective view showing the open state thereof;
FIG. 8 is a top, rear, and right perspective view showing the open state thereof;
FIG. 9 is an enlarged view of portion 9 shown in FIG. 5;
FIG. 10 is an enlarged view of portion 10 shown in FIG. 6;
FIG. 11 is an enlarged view of portion 11 shown in FIG. 8;
FIG. 12 is a front view thereof, shown with the lens cover in a closed position;
FIG. 13 is a rear view thereof;
FIG. 14 is a right side view thereof;
FIG. 15 is a left side view thereof;
FIG. 16 is a top view thereof;
FIG. 17 is a bottom view thereof;
FIG. 18 is a top, front, and left perspective view showing the close state thereof;
FIG. 19 is a top, rear, and right perspective view showing the close state thereof;
FIG. 20 is an enlarged view of portion 20 shown in FIG. 16;
FIG. 21 is an enlarged view of portion 21 shown in FIG. 17;
and,
FIG. 22 is an enlarged view of portion 22 shown in FIG. 19.
The broken lines depict portions of the camera that form no part of the claimed design. The dot-dash broken lines encircling an enlargement portion of the design forms no part of the claimed design.
